PUSHER PLATE

Wilhelmus Adrianus van Berkel, Clarens, Switzerland, assignor to U. S. Slicing Machine Company, La Porte, Ind., a corporation of Indiana

Application October 20, 1933, Serial No. 694,378
In Great Britain November 4, 1932

11 Claims. (Cl. 146—217)

The present invention relates to slicing machines and particularly to that type of slicing machine which includes a slicing knife, gauge plate, substance support, and pusher plate, the latter being manually or spring pressed toward the cutting plane of the knife and gauge plate.

In slicing machines of this type generally speaking, it is desirable to have as narrow a slicing machine as possible in order that the same will not occupy too great a space. Furthermore, most substances which are sliced in delicatessen stores and the like are not extremely long and therefore the width of the slicing machine ordinarily does not have to be very great. Sometimes, however, it becomes necessary to slice longer substances and the narrow slicing machines are not equipped to handle the same, at least with a positive feed, as the pusher plates which are used generally have a travel which does not exceed the width of the substance supporting table.

The present invention, therefore, has for one of its objects the provision of feeding means for feeding substances which are longer than the normal permitted feed for the pusher plate.

Another object of this invention is to provide a pusher plate which is positively guided and which can, if desired, be used to feed a substance which is longer than the width of the slicing machine table in the direction of feed of the substance. The pusher plate is so mounted as to permit the long substance to be fed toward the cutting plane of the knife with the pusher plate at the rear end of the substance until the substance has had some slices cut therefrom sufficient to make the substance materially shorter than originally, after which the position of the pusher plate is changed with respect to its mounting so that the remaining part of the substance is fed the same as the ordinary short piece of substance which is sliced on machines of this character.

A still further object of this invention is to provide a positive feed for a pusher plate along a plurality of similar paths of substantially the same extent but varying with respect to the substance supporting table or carriage.

Another object of this invention is to provide an adjustable pusher plate or work-feeding member which is adjustable relative to its feeding means in a direction toward and away from the cutting plane of the knife, and independently of the feeding movement of the feeding means. This is to enable one to slice long substances as well as short substances on a slicing machine

table which is designed primarily to accommodate only short substances.

Another object of this invention is to provide a feeding means for feeding the substance comprising either a power or manually fed member having a limited path of travel to which a feeding member such as a clamp or pusher plate may be connected at different positions with respect thereto in a direction perpendicular of the cutting plane of the knife, or in the direction of feed of the substance.

Another object of this invention is to provide a feeding means which embodies an actuating member and a substance engaging member adapted to be secured thereto in any one of a plurality of relative positions spaced from each other in the direction of feeding movement whereby substances of greater length may be sliced by the slicing machine.

Other objects of this invention will appear hereinafter as the description of this invention proceeds, the novel features, arrangements, and combinations being clearly set forth in the specification and claims.

In the drawings:

Fig. 1 is a side elevational view of a slicing machine embodying my invention;

Fig. 2 is a view looking in the direction of the arrows 2—2 of Fig. 1;

Fig. 3 is a section taken along the line 3—3 of Fig. 1;

Fig. 4 illustrates a modified form of my invention;

Fig. 5 is a cross-section taken substantially along the line 5—5 of Fig. 4;

Fig. 6 is a vertical cross-sectional view through a modified slicing machine table embodying my invention;

Fig. 7 is a view looking in the direction 7—7 of Fig. 6;

Fig. 8 is a cross-section taken substantially along the line 8—8 of Fig. 7;

Referring now particularly to Figs. 1, 2, and 3, the reference character 10 indicates a slicing machine knife driven by a motor 11 through the intermediary of a belt or chain 12, or in any other suitable manner. It may even be driven by the same means which actuates the carriage.

The base of the slicing machine 13 has a plurality of guide rods 14 and 15 which slidably support a substance carriage 16 having an operating handle 17 for reciprocating the carriage along the guide rods 14 and 15. A gauge plate 18 having the operative face thereof substantially in the cutting plane of the knife is adjusted to

various desired positions parallel to the cutting plane of the knife by means of an actuating knob 19 in a manner which is well known in the art to which this invention pertains.

5 The substance is mounted on the supporting surface 20 of the carriage which is formed as a V-shaped trough, the sides of which both extend upwardly but in opposite directions away from a horizontal plane as is clearly illustrated 10 in Fig. 1. Mounted on the substance supporting carriage 16 beneath the supporting surface 20 are a pair of guide rods 21 on which a bearing 22 slides. The bearing member 22 has a portion extending to the right of the carriage as 15 viewed in Figs. 1 and 2, and this part of the bearing member carries the uprights 23 which guide a pusher plate support 24 for movement in an upward direction.

As is best illustrated in Figs. 2 and 3, the support 24 has a pivot 25 on which a plate 26 is pivoted. This plate carries a substance pusher plate 27 having prongs 28 extending outwardly from opposite sides thereof with additional prongs 29 extending from the upper and lower edges thereof as is clearly illustrated in Figs. 1 and 3. This pusher plate 27 is secured rigidly to the plate 26 and moves therewith. The pusher plate 27 carries a rearwardly extending pin 30 which is adapted to engage limiting stops 31 on 30 the support 24 so that the same can be moved to either the full line position or dotted line position and held by gravity in either of said positions with the pin 30 against one or the other of the stops 31. A simple manual movement of 35 the pusher plate 27 brings the pusher plate into either position which may be desired.

Since the pusher plate is provided with prongs 28 on the opposite sides thereof and on the upper and lower edges thereof, the pusher plate 40 will always have prongs disposed toward the cutting plane of the knife and toward the substance supporting surface 20, no matter which of its positions it occupies. Intermediate positions for the plate 27 may be provided if desired.

45 Surrounding one of the guide rods 21 is a coiled spring 32 which abuts at one end thereof against the bearing 33 for the guide rod and at the other end against the bearing member 22. As the spring expands, the bearing member 22 and consequently the pusher plate 27 is moved toward the cutting plane of the knife to maintain the forward edge of the substance against the gauge plate 18 which latter gauges the thickness of the slice to be formed.

50 When the pusher plate is in the dotted line position shown in Fig. 3, it lies closely adjacent the cutting plane of the knife with the prongs 28 almost in the cutting plane of the knife while when the pusher plate is in the full line position shown in that figure, the prongs on the operative face thereof lie farther from the cutting plane of the knife although the position of the support 24 is unchanged. Therefore, when the substance to be sliced is long, the pusher plate is moved to the position shown by full lines in Fig. 3 so as to have a greater distance between the operative face thereof and the cutting plane of the knife. The bearing member 22 is moved away from the cutting plane of the knife against the action of 65 the spring 32 as far as possible, and the substance placed between the pusher plate 27 and the gauge plate. The pusher plate is then released and the plate acts to feed the substance in the usual manner. When the support 24 has been moved to 70 toward the cutting plane of the knife as far as pos-

sible with the pusher plate in the full line position shown in Fig. 3, the bearing member 22 is again retracted against the action of the spring 32 and the pusher plate 27 moved to the dotted line position with respect to the support 24. This brings the other face of the pusher plate opposite the end of the substance which is now quite short, and the spring 32 will feed the substance until the ends of the prongs 28 are substantially in the cutting plane of the knife but just slightly spaced 10 therefrom. Therefore, it will be seen that with a pusher plate constructed as set forth herein, a longer substance may be sliced than is permitted by the normal travel of the bearing member 22. Therefore, if the travel of the bearing member 22 15 is made maximum for the width of the slicing machine carriage in a direction perpendicular to the cutting plane of the knife, one can get the benefit of a still longer travel of the bearing member by adjusting the position of the pusher plate 20 27 in the manner which has been set forth.

In addition to utilizing the pusher plate 27 solely as a pusher plate arranged behind the substance, one can use the same for a top clamp by sliding the support 24 upwardly along the uprights 23 and bringing the support downwardly to press the prong 29 into the substance, the feeding then taking place in the usual manner, or the same can be used for feeding substances toward the cutting plane of the knife by engagement with the top thereof merely by a pivoting movement of the plate 27 into engagement with the top side of the substance without moving the support 24 along the uprights.

As has already been pointed out, the full line position of the pusher plate shown in Fig. 3 is used for the longer substances. These substances sometimes hang over the edge of the substance carriage, and this overhanging portion tends to increase the frictional resistance to the advance 40 of the substance toward the cutting plane of the knife. This is particularly true of thin substances, such as bacon. However, the prongs which engage a slab of bacon or the like, are situated below the pivot 25. Therefore, as the substance is advanced toward the cutting plane of the knife by the pusher plate, there is a tendency for the pusher plate, due to the reactionary pressure of the bacon against the plate, to rotate in a counter-clockwise direction from the position indicated 45 in Fig. 3 by full line. This lifts the bacon slightly, and reduces the frictional contact between the lower side of the slab of bacon and the substance supporting carriage, 16. There is a sufficient amount of the bacon in contact with the substance supporting carriage 16 near the cutting plane of the knife to resist any substantial amount of lateral shifting movement of the same during 50 the slicing operation.

With a shorter substance however, there is less 60 weight on the substance carriage, and consequently the amount of friction which resists lateral shifting movement of the substance during slicing of the same is reduced. However with the pusher plate in the dotted line position shown in Fig. 3, 65 the reactionary pressure is such as to tend to force the pusher plate in a counter-clockwise direction, and if the pin 30 is not in engagement with the stop 31, the reactionary pressure will tend to force the bacon down against the supporting surface of the substance carriage. Or the bacon can be held in greater frictional engagement with the substance supporting carriage by having the prongs 29 engage the upper side of the slab of bacon with the pusher plate tilted at a slight 70 75

angle to the vertical. Thus, when the overhang of the substance tends to increase the frictional resistance to the advance of the substance, the same may be reduced and also when the frictional resistance to the lateral shifting of the substance is lessened due to the shorter substance, this resistance can be increased in the manner set forth. This use of my invention is not limited solely to thin substances such as slabs of bacon, for due 10 to the fact that bearing 24 can slide along rod 23, the pivot 25 can always be placed at a position above the upper side of the substance. With the pivot 25 above the upper side of the substance, or the portion of the substance contacted by the 15 pusher plate, the aforesaid result will occur.

In Figs. 4 and 5, I have shown a modified construction in which the uprights 23 carry a pusher plate support 34 to which are pivoted at 35 the links 36 and 37 which in turn have pivotal connection at 38 with the pusher plate 39 having prongs 40 on the said face thereof and prongs 41 on the lower edge thereof. A locking pin 42 is pressed by a spring 43 toward the support 34 and is adapted to enter openings 44 or 45 depending 20 upon whether the links and pusher plate occupy the full or dotted line position respectively. With this construction, it will be noted that prongs are necessary only on the forward face of the pusher plate and at the lower edge thereof since 25 the pusher plate moves from one position to the other through positions all of which are parallel to each other, thus maintaining the same operative face of the pusher plate facing the cutting plane of the knife at all times. The device operates 30 in the manner set forth in connection with the form of the invention shown in Figs. 1 to 3 inclusive.

In Figs. 6, 7 and 8 I have illustrated a modification of my invention which is somewhat similar 40 to that disclosed in Figs. 1 and 2, but in this modification the bearing member 46 which corresponds to the bearing member 22 in Fig. 2 has an extension 47 secured thereto extending toward the operator's side of the slicing machine table 45 48 rather than toward the side away from the operator. This extension 47 has a reduced neck portion 48 and an elongated portion 49 outside of the casting 50 to which there is secured, in a manner which I will describe, a pusher plate 51 50 having substance engaging prongs 52 thereon.

This pusher plate 51 is preferably formed from a single sheet of material from which the prongs 52 are struck up and from which the reinforcing flanges 52¹ and bearing member 53 are formed 55 by suitable stamping operations, although it is to be understood that this pusher plate may be formed in any other manner as desired. A bracket 54 has the parallel slots 55 in the lower edge thereof and these embrace a pair of thumb screws 56 threaded into suitable openings in the portion 49 of the bracket 47. There are preferably three or more threaded openings 57 in the portion 49 spaced equal distances from each other so that the threaded thumb screws 56 may be 60 put into any adjacent pair of openings. By this arrangement the threaded thumb screws 56 may be placed in different pairs of openings so that the bracket 54 is located at different positions with respect to the bearing member 47 in the 65 direction of feed of the bearings 47, whereby the path of travel of the pusher plate may be varied although the extent of its travel when connected to the bracket 54 remains the same. Thus if the thumb screws 56 in Fig. 7 were placed in the two 70 threaded openings at the right instead of the two 75

threaded openings at the left shown in that figure, it is obvious that a longer piece of substance may be fed than when it occupies the position shown in Fig. 7. This is for the same purpose as has been explained in connection with Figs. 1-4 5 inclusive of the drawings. Instead of having slots and thumb screws as shown in Fig. 7, I could provide a longitudinal slot in the lower edge of the bracket 54 with a thumb screw or thumb screws extending therethrough into the portion 10 49. With such an arrangement it would only be necessary to loosen the thumb screws and slide the bracket along the portion 49 and then tighten the thumb screws again in order to secure adjustment of the bracket 54, and consequently of the 15 pusher plate 51.

The bearing portion 53 on the pusher plate 51 is pivoted to the bracket 54 at 58 so as to have pivotal movement for the same purpose as the pivotal movement of the pusher plate in Figs. 1 20 and 2. The pivotal movement of the pusher plate is limited by the stops 59 and 60, the latter limiting the movement of the pusher plate and locating the face thereof parallel to the cutting plane when the prongs are facing the cutting plane, and the former limiting the position of the pusher plate 25 in a parallel position to that shown in Fig. 7 with the prongs extending away from the cutting plane of the knife.

Obviously those skilled in the art to which this 30 invention pertains may make various changes in the particular construction and arrangement of parts without departing from the spirit of this invention and therefore I do not wish to be limited except as hereinafter set forth in the appended claims.

Having thus fully described my invention, what I claim as new and desire to obtain by Letters Patent is:

1. In a slicing machine, the combination with 30 a slicing knife, of a substance support movable relative to said slicing knife, uprights on said substance support, a bearing member for supporting said uprights and slideable along said support in a direction toward and from the cutting 45 plane of said knife, a pusher plate support slideable upwardly along said uprights, a pusher plate, an extension on said pusher plate having pivotal connection with said pusher plate support at a point spaced from the operative portions of said 50 pusher plate, whereby upon pivotal movement of said pusher plate, the same is swung to positions which are spaced substantially different amounts away from the cutting plane of said knife while said bearing member occupies the same position 55 with respect to the cutting plane, and substance engaging prongs on opposite faces of said pusher plate whereby when said pusher plate is pivoted to its different positions and different faces thereof are facing the cutting plane of said knife, the 60 portion which is facing said cutting plane will have substance engaging prongs thereon.

2. A slicing machine comprising a substance support, a bearing member slideable along said support, a pusher plate having substantially parallel faces with outwardly projecting prongs extending away from each other, an extension for said pusher plate having pivotal connection with said bearing member eccentric to the faces of said pusher plate but substantially parallel to the faces thereof, whereby upon pivotal movement of said pusher plate about said pivotal connection through substantially 180 degrees, the faces thereof are caused to face in opposite directions to those directions in which they originally 75

faced, and position locating means for locating said pusher plate in either of said positions to which the same may be moved.

3. In a slicing machine, the combination with a substance support, of a slicing knife, means for moving said substance support and slicing knife relative to each other, a bearing member 5 slidable along said support in a direction toward the cutting plane of said knife, a pair of links 10 pivotally connected to said bearing member, a pusher plate, pivotal connections between said pusher plate and the opposite ends of said links, said pivotal connections extending in a direction transversely to the path of movement of said bearing member, whereby upon angular movement 15 of said links about their pivotal connections with said bearing member, the pusher plate is moved to successive positions substantially parallel with its original position but at different 20 distances from the cutting plane of said knife.

4. In a slicing machine, the combination with a substance support, of a slicing knife, means for moving said substance support and slicing knife relative to each other, a bearing member 25 slidable along said support in a direction toward the cutting plane of said knife, a pair of links pivotally connected to said bearing member, a pusher plate, pivotal connections between said pusher plate and the opposite ends of said links, said 30 pivotal connections extending in a direction transversely to the path of movement of said bearing member, whereby upon angular movement of said links about their pivotal connections with said bearing member, the pusher plate is moved 35 to successive positions substantially parallel with its original position but at different distances from the cutting plane of said knife, and means maintaining said pusher plate in a plurality of selected positions to which the same can be moved. 40

5. In a slicing machine, the combination with a substance support, of a slicing knife, means for moving said substance support and slicing knife relative to each other, a bearing member 45 slidable along said support in a direction toward the cutting plane of said knife, a pair of links pivotally connected to said bearing member, a pusher plate, pivotal connections between said pusher plate and the opposite ends of said links, said 50 pivotal connections extending in a direction transversely to the path of movement of said bearing member, whereby upon angular movement of said links about their pivotal connections with said bearing member, the pusher plate is moved to successive positions substantially 55 parallel with its original position but at different distances from the cutting plane of said knife, and means maintaining said pusher plate in a plurality of selected positions to which the same can be moved, said means comprising a locking 60 pin for locking the position of said links with respect to said bearing member.

6. In a slicing machine, the combination with a substance support, of a slicing knife, means for moving said substance support and slicing knife 65 relative to each other, a bearing member slidable along said support in a direction toward the cutting plane of said knife, a pair of links pivotally connected to said bearing member, a pusher plate, pivotal connections between said pusher plate and the opposite ends of said links, said 70 pivotal connections extending in a direction transversely to the path of movement of said bearing member, whereby upon angular movement of said links about their pivotal connections with said bearing member, the pusher plate is

7. In a slicing machine, the combination with a substance support, of a slicing knife, means for moving said knife and support relative to each other, a pusher plate, a bearing member for supporting said pusher plate and having a limited path of travel with respect to said substance support in a direction toward and from the cutting plane of said knife, and an operative connection between said pusher plate and said bearing member adjustable to vary the position of the bearing member and pusher plate relatively to each other in a direction toward and from the cutting plane of said knife, whereby said pusher plate may be moved to limiting positions adjacent to and remote from the cutting plane of said knife which are spaced from each other a distance which is substantially greater than the permitted travel of said bearing member and while positively connected to said bearing member for movement therewith, said pusher plate in moving from one position to another position with respect to said bearing member moving through successive intermediate positions all of which are parallel to each other.

8. In a slicing machine having a gauge plate and a rotary knife, a pusher plate adapted to push substance toward the gauge plate and toward the cutting plane of the knife, spring means for giving limited movement to the pusher plate toward the gauge plate and said plane, said pusher plate being pivotally mounted on an axis parallel to the cutting plane of the knife whereby the pusher plate may be pivoted on its axis to bring another side of the pusher plate into position for engagement with the substance, thereby having opposing surfaces of the pusher plate capable of engagement with the end of the substance to accommodate both short and long substances, said pusher plate also having engaging means on its upper and lower surfaces to engage the substance regardless in which direction the opposing faces of the pusher plate are positioned.

9. In a slicing machine, a knife and a gauge plate parallel to the plane of the knife, a carriage reciprocable past the gauge plate and knife, an upstanding member on said carriage, a pusher plate having at least two parallel substance engaging surfaces, a member extending at right angles to both substance engaging surfaces and pivoted to said upstanding member at a point displaced from the parallel substance engaging surfaces whereby the pusher plate may be swung on its pivot in a vertical plane and move the same farther from or closer to the cutting plane to accommodate long as well as short pieces of substance.

10. In a slicing machine, a knife and a gauge plate parallel to the plane of the knife, a carriage reciprocable past the gauge plate and knife, a pusher plate and means mounting the pusher plate so that it can be swung into two positions, one nearer the knife plane and generally parallel thereto, and the other further from the knife plane and generally parallel thereto, said means

comprising a member attached to the pusher plate adjacent an edge thereof, upright means positioned on said carriage, pivotal means offset from the plane of the pusher plate and connecting said member to said upright means, said member, upright means and pivotal means being positioned out of obstructing relationship with the material being fed when the pusher plate is in either of its two operative positions.

10 11. In a slicing machine, a knife and a gauge plate parallel to the plane of the knife, a carriage reciprocable past the gauge plate and knife, a pusher plate and means mounting the pusher plate so that it can be swung through an arc of

180 degrees and rigidly held in either of two positions, one nearer the knife plane and generally parallel thereto, and the other further from the knife plane and generally parallel thereto, said means comprising a member attached to the 5 pusher plate adjacent an edge thereof, upright means positioned on said carriage, pivotal means offset from the plane of the pusher plate and connecting said member to said upright means, said member, upright means and pivotal means being 10 positioned out of obstructing relationship with the material being fed when the pusher plate is in either of its two operative positions.

WILHELMUS ADRIANUS VAN BERKEL.
